DESIGN FOR A NUTCRACKER

Ernest J. Carlson, Reading, Pa.

Application February 5, 1944, Serial No. 112,457

Term of patent 3½ years

(Cl. D89—1)

To all whom it may concern:

Be it known that I, Ernest J. Carlson, a citizen of the United States, residing at Reading, in the county of Berks and State of Pennsylvania, have invented a new, original, and ornamental Design for a Nutcracker, of which the following is a specification, reference being had to the accompanying drawing, forming part thereof.

Fig. 1 is a top plan view of a nutcracker, show-

ing my new design;

Fig. 2 is a side elevational view;

Fig. 3 is an end elevational view; and

Fig. 4 is a side perspective view thereof.

What I claim is:

The ornamental design for a nutcracker, as shown.

ERNEST J. CARLSON.
